HUDSON MOTOR CAR COMPANY, OF DETROIT, MICHIGAN, A CORPORATION OF
MICHIGAN

STRIPING DEVICE FOR AUTOMOBILE BODIES

Application filed April 23, 1928. Serial No. 272,071.

This invention relates to a portable device and a method for striping automobile bodies, and more especially for striping along or adjacent the belt line molding and window reveals of the body.

An object of the invention is to provide a device or apparatus of the foregoing character having force feed mechanism adapted to supply paint or other fluid to the applicator of the device in proportion to the speed of movement of the device over the surface to be striped. Another object of the invention is to provide automatic means engageable with the automobile body for actuating the force feed mechanism. Further objects of the invention consist in the provision of guide means for the applicator and a handle for the device mounted for adjustment relative to the means for actuating the force feed mechanism; and to provide applicators of different forms which are capable of producing both narrow and wide stripes.

The above and other objects of the invention will be apparent from the following description and appended claims when taken in conjunction with the accompanying drawings wherein like reference characters designate similar parts in the several views.

In said drawings:

Fig. 1 is a perspective view of one form of striping device embodying the invention.

Fig. 2 is a top plan view of the device of Fig. 1.

Fig. 3 is a section on the line 3—3, Fig. 2.

Fig. 4 is an enlarged section along the line 4—4 of Fig. 3.

Fig. 5 is a side elevation of the device of the preceding figures showing the application of the device to a body having a sloping side.

Fig. 6 is a view similar to Fig. 1 showing a modified form of applicator.

Fig. 7 is a plan view of the device of Fig. 6.

Fig. 8 is a section on the line 8—8 of Fig. 7.

Fig. 9 is a detail side elevation, partly in section, of the applicator of Figs. 6 to 8 inclusive.

Fig. 10 is a detail sectional view taken on the line 10—10 of Fig. 9, and

Fig. 11 is a side elevation of the apparatus of Figs. 6 to 10 inclusive showing the applica-

tion thereof to a body having a sloping side.

Before explaining in detail the present invention, and the method of operation embodied therein, it is to be understood that the invention is not limited in its application to the details of construction and arrangement of parts illustrated in the accompanying drawings, since the invention is capable of other embodiments and of being practised or carried out in various ways. Also it is to be understood that the phraseology or terminology employed herein is for the purpose of description and not of limitation, and it is not intended to limit the invention beyond the terms of the several claims hereto appended or the requirements of the prior art.

Referring now to Figs. 1 to 5 inclusive of the drawings, the striping device or apparatus of our invention may comprise a tank or reservoir 10 having an extension 11 to which is pivotally connected a handle 12 maintained in fixed adjusted position by means of a bolt and wing nut construction 13. Mounted upon the reservoir 10 through the medium of an extension or projection 14 is one form of applicator embodying our invention. This applicator comprises preferably a pen having a pair of nibs 15, 15 each preferably hinged at 16 to the body extension 14, the nibs being adjustable relatively to one another by means of an adjusting screw 17.

As best seen in Fig. 1, the reservoir supports a guiding device for the pen or applicator which is mounted upon a frame comprising upright rods 18 and horizontal parallel bars 19, the ends of the members 18 being bent at an angle to their upright portions and connected in any suitable manner with the reservoir at 18a. The guiding device comprises a socket member 20 preferably rectangular in cross section having an apertured lateral projection or extension 21 and a slotted extension 22. The socket member 20 is adjustable vertically upon the rods 18 and is maintained in any desired adjusted position by means of a clamping screw 23. The outer face of the socket member adjacent its forward end is provided with a slot

24. The socket carries preferably a spring pressed plunger 25 having at its outer end a body engaging guide member 26. The member 25 is provided with a lateral pin 25a which projects through the slot 24 when the parts are assembled, this pin serving to limit the movement of the member 25 relative to the socket. A coil spring 26a (Fig. 2) is positioned within the socket member behind the plunger and serves to maintain it normally in projected position.

10 The lower end of the reservoir is reduced to provide a neck portion 10a and is internally threaded to receive a threaded plug 27 (Fig. 3). The plug is provided with a central bore for a purpose to be hereinafter described. An apertured screw threaded cap member 28 engages the threads of the plug 27 and supports between it and the outer end of the plug, packing material 29. Mounted upon the cap for rotary movement thereupon is a preferably frusto-conical roller member 30 having a hub portion 31 between which and the exterior of the cap 28 a ball race and bearings 32 are supported. A shaft 33 extends through the bore in the plug 27 and through the apertured cap and is pinned at 34 to the hub 31 of the roller. Mounted upon the inner portion of the shaft is a ring or collar 35 between which and the inner end of the plug 27 a ball race and bearings 36 are supported. The shaft and roller are held in position by means of a pin 37 which connects the shaft and collar 35.

35 Mounted within the reservoir and extending from a point adjacent the inner end of the shaft 33 is preferably a conveyor tube or conduit 38 having a lower flared end portion 39. The upper end of the tube is detachably connected through the medium of a threaded collar 40 with an integral threaded nipple 10b which may be formed upon the reservoir 10. The reservoir 10 is provided with an exterior internally threaded nipple 45 10c to which a feed tube or pipe 41 is threaded (Fig. 4).

It is important that paint or other fluid be fed from the reservoir to the pen through the feed tube 41, and to accomplish this purpose we provide preferably a flexible spiral conveyor screw 42 which is connected at its lower end with the shaft 33 and extends to a point within the inner end of the feed tube 41 as best shown in Fig. 4. It will be understood that rotation of the roller 30 transmits rotary movement to the feed screw 42 thus feeding the liquid upwardly through the pipe 38 and feed tube 41 to the pen nibs 15. The ball race and bearings prevent binding of the parts when the device is in use and permit the free rotation of the roller, shaft and feed screw.

From the foregoing it will be seen that when the reservoir 10 contains a supply of paint, the pen 15 and the guide 26 are brought

70 into engagement with the body panel B at which time the roller 30 is also brought into engagement with the panel. Movement in either direction of the apparatus across the surface of the panel B will cause the paint to be fed to the pen which pen in turn applies the stripe S to the body (see Fig. 1). It will also be understood that the amount of paint or other fluid fed to the pen is controlled and regulated in proportion to the speed of movement of the device so that when the device is operated rapidly a greater supply of paint is fed to the pen than when said device is moved more slowly across the surface, thereby producing an even flow of paint and an even stripe.

75 The apparatus of Figs. 6 to 11 is identical with that of the preceding figures with the exception of the applicator. In these latter figures the reservoir 10 is provided with an extension 140 having branches or projecting portions 141, 142 and 143. Mounted upon the branches 141 and 143 are a pair of striping pens each comprising a pair of nibs 150, 150 which are perfectly identical with the nibs 15 of the device of Fig. 1, these being provided with the usual adjusting screws 170, 170, and being screw threaded upon the extensions as shown at 151, 151 in Fig. 9. Interposed between the pens is a third applicator which, in the present instance, is a striping brush 152 comprising a socket portion 153 threaded to the extension 142 as shown at 154. Embedded in the brush 152 is the flared and flattened nozzle portion 156 of an auxiliary feed tube or pipe 155. The pens are each provided with a feed tube or pipe 150a which extend to a point adjacent the tips of the nibs 150. The tubes 155 and 150a serve to conduct the paint or other fluid to the brush and the striping pens, respectively, it being forced through the medium of the roller 30 and feed screw 42 to the orifices 140a in the extension 140. When the device is to be operated the ring 26 of the guide is brought into engagement with the body panel and the striping pens 150 and interposed brush 152 brought into engagement with the body panel at the point where a wide stripe is to be made, while at the same time the roller 30 engages the panel. With the parts in this position the handle 12 is grasped by the operator and the device moved across the body of the automobile thus producing a relatively wide stripe at the point desired. As in the case of the device of Figs. 1 to 5 inclusive, the amount of paint supplied to the pens and brush is controlled in accordance with the speed of movement of the device, there being a greater supply fed to the applicator when the apparatus is moved rapidly across the surface than when the device is operated more slowly.

80 It will be understood that the spring pressed guide member 26 permits the device to accommodate itself to uneven surfaces

without marring the body paint and without interrupting the evenness of the stripe.

As shown in Figs. 5 and 11 it is sometimes desirable to apply stripes to a sloping body panel. When operating upon such surfaces, the wing nut 13 is loosened whereupon the handle may be moved to a strictly vertical position as shown in these figures so as to prevent any possibility of awkwardness in the operation of the device, it being understood that the handle is adjusted relatively to the roller 30.

The device is capable of applying a stripe directly to the belt panel molding BP if desired. Moreover, the device is capable of applying stripes to the window reveals of body panels in which case the guide members are brought into engagement with the edge of the window reveal.

It will, of course, be understood that the cap or closure for the reservoir 10 in both forms is provided with an air vent 100.

It will be seen that by means of the construction shown in Figs. 6 to 11 inclusive, we are able to provide a relatively wide stripe on the body in a single operation. This may be done, in accordance with our present method, by simultaneously applying three stripes, namely two spaced parallel stripes and a relatively wider intermediate stripe overlapping slightly the marginal stripes, thereby producing a single uniform stripe. The pens 150 produce even and well defined margins, and the intermediate applicator or brush 152 provides a filler stripe between the marginal stripes.

We claim:

1. In a striping device, the combination of a reservoir for striping fluid, an applicator, a tube leading from said reservoir to the applicator, a screw extending through said tube for feeding the fluid from the reservoir to the applicator, and a roller adapted to travel on the surface to be striped for operating said screw.

2. In a striping device, the combination of a reservoir for striping fluid, an applicator, a tube leading from said reservoir to the applicator, a flexible rotary propeller extending through said tube for feeding the fluid from the reservoir to the applicator, and a roller adapted to travel on the surface to be striped for rotating said propeller.

3. In a striping device, an applicator, a reservoir communicating with said applicator, a flexible screw conveyor positioned within said reservoir for supplying fluid to the applicator, and a friction roller of relatively softer material than the surface to be striped engageable with said surface for driving the conveyor.

4. In a striping device, the combination of an applicator, a fluid tank normally located below the level of the applicator, a tube having an inlet opening in the reservoir ad-

jacent the bottom thereof and an outlet adjacent the applicator, a rotary spiral propeller within said tube, and means carried by the device for rotating said propeller to feed fluid from the bottom of the reservoir to the applicator.

5. In a striping device, the combination of a tank for the striping fluid, an applicator, a conduit having an inlet opening adjacent the bottom of the tank and an outlet adjacent the applicator, a rotary device mounted within the tank and extending into said conduit for feeding the fluid from the bottom of the tank through the conduit to the applicator, and a roller adapted to travel on the surface to be striped for operating said rotary device to supply fluid to the applicator in proportion to the speed of movement of the applicator.

6. In a striping device, the combination of a reservoir for striping fluid, an applicator, a guide for the applicator carried by the reservoir, a tube leading from said reservoir to the applicator, a flexible rotary propeller extending through said tube for feeding the fluid from the reservoir to the applicator, and a roller adapted to travel on the surface to be striped for rotating said propeller.

7. In a striping device, an applicator, a reservoir communicating with said applicator, a guide for the applicator carried by said reservoir, a flexible screw conveyor positioned within said reservoir for supplying fluid to the applicator, and a friction roller of relatively softer material than the surface to be striped engageable with said surface for driving the conveyor.

8. In a striping device, the combination of an applicator, a reservoir for containing striping fluid, a guide for said applicator carried by the reservoir, a tube having an inlet opening adjacent the bottom of the reservoir and an outlet adjacent the applicator, a rotary spiral propeller within said tube, and means carried by the device for rotating said propeller.

9. In a striping device, the combination of an applicator, a fluid tank normally located below the level of the applicator, a guide for said applicator carried by said fluid tank, a tube having an inlet opening in the reservoir adjacent the bottom thereof and an outlet adjacent the applicator, a rotary spiral propeller within said tube, and means carried by the device for rotating said propeller to feed fluid from the bottom of the reservoir to the applicator.

In testimony whereof we affix our signatures.

RALPH Z. HOPKINS.
